HEATING SYSTEM.

1,103,215.

Specification of Letters Patent.

Patented July 14, 1914.

Application filed October 29, 1913. Serial No. 798,019.

To all whom it may concern:

Be it known that I, FRANCIS H. MONTREUIL, a citizen of the United States, residing at Chicago, in the county of Cook 5 and State of Illinois, have invented a certain new and useful Improvement in Heating Systems, of which the following is a specification.

This invention relates to heating systems 10 and has for its object to provide a new and improved system of this description and is particularly adapted for steam heating systems where steam pumps, cookers, etc., are run from the same boiler supplying steam 15 for the heating system. It is customary in such systems to provide a reducing valve arranged to supply steam at a reduced pressure to the heating system in response to the demand for the steam in the heating system.

20 When pumps, cookers and the like are operated from this same boiler as the heating system, and particularly where the pump is connected with the return line or air line of the system, such a system is defective in 25 that it often happens that the heating system takes steam from the boiler in such quantities as to reduce the pressure below that required to operate the pump and other devices, thus causing the pump to stop, the 30 system then becomes clogged, fails to properly heat the building and remains in this condition until the pump can be started up so as to clean out the heating system and cause it to again operate properly.

35 One of the objects of my invention is to prevent the heating system from thus robbing the boiler and to so conserve or retain the steam in the boiler so as to maintain at all times, when the boiler is in operation, a 40 steam pressure sufficient to run the pump, cookers and the like.

My invention is illustrated in the accompanying drawings, wherein—

Figure 1 is a diagrammatic view showing 45 one form of my system; Fig. 2 is a sectional view showing the detailed view of the controlling valve between the boiler and the heating system.

Like numerals refer to like parts 50 throughout the several figures.

Referring now to Fig. 1, I have shown a boiler 1, provided with a steam main 2, which conducts the steam to the different parts of the heating system throughout the 55 building. I have shown the main as pro-

vided with the risers 3, connected with the radiators 4, the radiators being also connected with the return pipes 5, connected with the pipe 6 leading to the air and water cylinder 7 of the pump 7^a. The pump 7^a has 60 a steam cylinder 8, which is connected by pipe 9 with the steam boiler. A conserving valve 10 is connected in the steam main 2. One form of this valve is illustrated in Fig. 2, wherein it is shown as consisting of the 65 movable valve pieces 11, engaging the valve seats 12, so as to control the flow of steam from the boiler side 13, to the steam system side 14. The valve pieces 11 are connected with a stem 15, which is operated by 70 a diaphragm in the casing 16. A pivoted lever 17 is connected with the valve stem 15 and is provided with the adjustable weight 18, which opposes the pressure of the steam in the boiler which enters the casing 16 75 through the pipe 19, said pipe communicating with the steam riser 2, or with the boiler in any other desired manner. The diaphragm and weight are so arranged that the valve pieces 11 will be moved to open the 80 valve only when the pressure in the boiler rises above that necessary to operate the pump. It will be seen that before the pressure in the boiler falls to a point too low to operate the pump, the valve will automatically close and conserve this pressure so as to insure the proper operation of the pump. The admission pipe 9 of the pump cylinder if connected with the steam main 2 is connected therewith on the boiler side of the 85 valve 10, the exhaust 20 of the pump may be connected to the steam main 2 on the steam heating side of valve 10 and an oil separator 21 may be placed in this exhaust. The air and water cylinder 7 of the pump 90 may be connected by a pipe 22 with the air separating device 23, the water being returned to the boiler through the pipe 24.

I have described in detail a particular construction embodying my invention, but it 100 is of course evident that this construction may be varied in many particulars without departing from the spirit of my invention. I have also shown a cooker 25 connected with the system, said cooker being provided 105 with the supply pipe 26 connected with the boiler, and the exhaust pipe 27 connected with the pump. I have also shown an automatic damper for controlling the door 28 of the furnace. This damper is of 110

the ordinary type and is worked by means of a chain 29 controlled by a diaphragm valve 30, which is connected by means of a pipe 31 with the steam main 2 on the steam heating side of the valve 10. The diaphragm valve 30 is arranged so that when the steam pressure in the steam heating system reaches a predetermined point this pressure actuates the valve 30 and causes the door 28 to close to shut off the draft to the furnace. When the pressure falls below this point the door automatically opens.

The operation of my invention is as follows: When the fire is started under the boiler, steam is generated and when the steam reaches a pressure sufficient to operate the pump, the pump begins to work and draws air from the heating system; as the pressure of the steam rises to the predetermined point, the valve pieces 11 are moved to admit steam to the main 2 on the steam heating side of the conserving valve, the steam then quickly passing to the different radiators. If now the pressure of the steam should fall below the predetermined point, the conserving valve will automatically close and prevent further escape of the steam into the heating system. The pump will still operate. It will be seen that when the steam is shut off from the heating system it will be comparatively easy to keep the pressure in the boiler high enough to operate the pump, because only a small

amount of steam is used. If on the other hand steam can pass freely into the heating system at all times, it will be seen that the heating system robs the boiler and the pump and when the fire burns low, reduces the pressure so as to stop the pump, the steam still passing into the heating system, and as there is no means of removing the water and air from the system, it will be seen that it then becomes clogged and the proper operation prevented.

I claim:

A steam heating system comprising a boiler, a steam main leading therefrom, a heater connected with said main so as to be supplied with steam, a return pipe connected with said heater, a pump connected with said return pipe, a steam pipe connecting the boiler with the pump to supply steam for operating the pump, an automatic valve in the steam heating main having means acted upon by the steam pressure from the boiler to hold the valve open and means for closing the valve when the steam pressure of the boiler falls below a predetermined amount.

In testimony whereof, I affix my signature in the presence of two witnesses this 21st day of October 1913.

FRANCIS H. MONTREUIL.
